SHAKING CONVEYER SYSTEM

Walter L. Herold, Scranton, Pa.

Application December 14, 1945, Serial No. 635,038

5 Claims. (Cl. 198—220)

1

This invention relates to shaking conveyors, particularly to means for driving a dependent shaker troughline from a distant troughline drive through fluid carried in conduits, the system being of such nature that the dependent troughline is driven in unison with the action of the main troughline drive no matter what may be the angular disposition or arrangement of the dependent troughline relative to the main troughline.

There are many situations where it is impractical to locate power drive means at the place where the troughline itself is located. For example, the fire hazard may bar the use of the power drive means at the troughline location. Usually this power means includes an electric motor and a spark from the motor may ignite inflammable gas. Or the space in which the troughline is located may be too small to permit the installation of power drive means, this being a relatively large and somewhat complex apparatus necessary to produce the particular motion required to cause the troughline to move material in a given direction.

The present invention provides means for transferring drive motion in a great variety of ways to a dependent troughline regardless of its location and disposition. For example, a passageway may have a turn which is too sharp for a continuous length of troughline. Here the troughline may be made in separate sections with one driven from the other by the interposition of relay drive means according to the present invention. There have been previous proposals for driving one conveyor line from another which is disposed at an angle relative thereto but such drive transfer devices have been wholly mechanical in nature involving such mechanisms as racks and gears or cables and pulleys which required the two troughlines to be disposed very close together and in a definite position when once fixed by the construction selected.

Again the present invention provides that a number of dependent troughlines may be driven from a single power drive means, either in series or in parallel or a combination of these.

The invention provides for making a drive connection into any given troughline and therefrom driving a dependent troughline which may be disposed in any position relative thereto. Any number of dependent drives may be inserted into a single troughline within the limits of power applied thereto. And to any one of these dependent troughlines similar relay drive connections may be applied.

2

One exemplary embodiment of the invention is illustrated in the accompanying drawings, wherein:

Fig. 1 is a sectional elevation of apparatus according to the present invention installed in a mine and wherein a plurality of dependent troughlines are driven by relay power means from a main troughline;

Fig. 2 is an enlarged elevation, partly in section, of a relay hydraulic device connected to a troughline, either for a driving or driven troughline;

Fig. 3 is a horizontal section taken on the line 3—3 of Fig. 2;

Fig. 4 is a transverse section taken on the line 4—4 of Fig. 2; and

Fig. 5 is a diagram of the relay drive fluid system.

As shown in Fig. 1, a main shaking conveyor troughline 10 may be disposed in a principal passageway 11. This passageway may be of sufficient size and sufficiently free from spark-ignitable gases to permit the main power drive unit to be mounted therein. This drive unit is well known and requires no illustration for an understanding of the invention.

An auxiliary or dependent shaking conveyor troughline 12 may be disposed in a smaller passageway 13 at a distance from the main troughline. The dependent troughline may be at any angle or position relative to the main troughline. It is shown above, to one side of, and extending laterally from the main troughline. It discharges into a chute 14 which in turn discharges into the main troughline.

Another auxiliary or dependent troughline 15 is shown in another passageway 16. The conveying arrangement of this dependent conveyor 15 relative to the main conveyor is not shown. It may discharge into the main conveyor directly or indirectly or it may discharge elsewhere. For present purposes it is sufficient to note that it is driven by a power relay system from one of the other troughlines illustrated, here the main one 10. It could, of course, be driven from the troughline 12 if desired by connecting the relay power unit to this instead of to the main troughline.

Each relay drive system includes a driven cylinder-and-piston unit 20, a driving cylinder-and-piston unit 21, and flexible conduit lines 22 connected between them. The driven unit is pump-like in character; while the driving unit may be compared to a motor. They work in unison, the motor being driven by fluid reciprocating in

the conduits. Practically the only difference between the driven or pump unit and the driving or motor unit is that the latter is made of enough greater capacity than the former to compensate for piston and joint leakage and flexible conduit expansion. The illustration and description of one will serve for both.

Each such unit may be referred to as a reciprocating hydraulic and one of the relatively moving parts is connected to a fixed anchorage and the other is connected to the driving or driven part, for example a troughline. Here the cylinder 25 is shown to be mounted on a base 26 which is held against the floor when convenient by jacks 27 braced against the ceiling. The rods 28 of piston 29 are connected to a bridge 30 which can be attached to a troughline in any convenient manner, either along a section or a joint between sections.

The bridge may be connected to the troughline in any suitable way. For example, it may carry brackets 35 to which anchor bolts 36 are secured, and the troughline may be provided with brackets 37 which are secured to or by the bolts. If two troughline sections are connected at the bridge, as shown in Figs. 2 and 4, the brackets of each may be shorter than the space between brackets 35 of the bridge but together or with fillers 38 are long enough to completely fill the space and prevent end play.

Guide rods 39 operating in guides 40 may be attached to the bridge to keep it and its piston in proper position. Both the piston rods 28 and the guide rods 39 may be attached to the bridge through the interposition of depending portions 41 secured to the bridge. Endwise protruding extensions 42 may be provided for direct power drive connection to the bridge when desired.

One relay operating system is shown in Fig. 5. Here the driven piston 29 of the pump-like hydraulic device 20 is understood to be connected to a power drive, commonly a power-driven troughline. It forces fluid, such as oil, which is relatively incompressible, alternately through one of the other of the conduits 22 connected to opposite ends of its cylinder 25. The fluid flows alternately to the opposite ends of the troughline driving cylinder 21 causing the piston 29 therein to move in unison with the piston 29 of the cylinder 20.

If leakage and other factors could be neglected the cylinder and conduits might simply be filled with liquid and the reciprocation of the driven piston would cause corresponding reciprocation of the driving piston. But because leakage cannot be neglected the cylinder 20 of the driven piston is made somewhat larger than the cylinder 21 of the driving piston, and certain auxiliary equipment is added to cause fluid to be circulated to and from a sump 45 instead of directly between cylinders. In conduits 22 sequence control valves 46 are interposed, these valves essentially comprising piston operated spring opposed valves which cause fluid to be returned to the sump through return conduits 47 instead of being returned to the cylinder 20. The valves are operated against their springs by fluid from the other side of the system, the fluid flowing through cross connection conduits 48. Excess pressure relief valves 49 are provided in relief conduits 50 connecting the conduits 22 and 47. Fluid flows from the sump to the cylinder 20 through supply conduits 51, check valves 52 being provided therein to prevent back-flow into the sump.

The relief valves can be used to regulate the

length of stroke of the driven conveyor line in order to adjust its carrying capacity to that of the conveyor which it serves.

The installation and operation of the apparatus will be clear from the foregoing description. It will be seen that a piston-cylinder device may be connected into any conveyor line at any desired point and connected by fluid-filled flexible conduits with a companion piston-cylinder device. When properly connected the reciprocation of one line will produce matched reciprocation of the other line.

While one embodiment of the invention has been described for purposes of illustration it will be apparent that there may be various embodiments within the limits of the prior art and the scope of the subjoined claims.

What is claimed is:

1. Shaking conveyor mechanism comprising in combination, a first reciprocating conveyor troughline, a double-acting reciprocating element of a fluid actuated piston-cylinder device connected to the first troughline, a second power-operated reciprocating conveyor troughline, a double-acting reciprocating element of a fluid-delivering piston-cylinder device connected to a second troughline, and flexible fluid-filled conduits between the opposite ends of the piston-cylinder devices establishing a fluid drive between them to cause them and their troughline to reciprocate in unison.

2. Shaking conveyor mechanism comprising in combination, a plurality of spatially separated shaking troughline conveyors, and fluid relay means including paired driven and driving piston-cylinder devices, one driven by one conveyor and the other driving the other conveyor and having a conduit carried reciprocating fluid drive therebetween whereby the conveyors are caused to move in unison when one of them is power driven.

3. Shaking conveyor mechanism comprising in combination, a plurality of spatially separated shaking troughline conveyors, and fluid relay means including paired driven and driving piston-cylinder devices, one driven by one conveyor and the other driving the other conveyor and having a conduit carried reciprocating fluid drive therebetween whereby the conveyors are caused to move in unison when one of them is power driven, the capacity of the fluid delivering piston-cylinder device being greater than the companion fluid-operated device, a sump from which the fluid-delivering device withdraws fluid, and means for diverting fluid returning from the driven device to the fluid delivering device to said sump.

4. Shaking conveyor mechanism comprising in combination, a first shaking conveyor troughline, a reciprocating liquid operated driving device therefor, a second power operated shaking conveyor troughline, a reciprocating liquid-delivering device operated by said second troughline, and liquid-filled conduits between the reciprocating devices establishing a liquid drive connection between them to cause the first to reciprocate in unison with the second.

5. Shaking conveyor mechanism comprising in combination, a driving piston hydraulic device connected to one conveyor line, a driven piston hydraulic device connected to another conveyor line, interconnecting fluid conduit lines between the hydraulic devices, a sump, return lines to the sump, supply lines from the sump to the driving piston hydraulic device, a by-pass line from the interconnecting lines to the sump, and a fluid

control valve in the bypass line for adjusting the action of the driven hydraulic device to the action of the driving hydraulic device.
